UNITED STATES PATENT OFFICE.

FRANÇOIS RICHARD, OF CLEVELAND, OHIO, ASSIGNOR TO THE RICHARD AUTO MFG. COMPANY, OF CLEVELAND, OHIO.

DESIGN FOR AN AUTOMOBILE-TOP.

51,268.

Specification for Design.

Patented Sept. 11, 1917.

Application filed May 2, 1917. Serial No. 166,059. Term of patent 14 years.

To all whom it may concern:

Be it known that I, FRANÇOIS RICHARD, citizen of the French Republic, residing at Cleveland, in the county of Cuyahoga and State of Ohio, have invented a new, original, and ornamental Design for an Automobile-Top, of which the following is a specification, reference being had to the accompanying drawing, forming part thereof.

Fig. II is a front elevation thereof.

Fig. III is a rear elevation of the same.

I claim:

The ornamental design for an automobile top as shown.

April 30, 1917.

FRANÇOIS RICHARD.
